UNITED STATES PATENT OFFICE.

HENRY FOLKMAN, OF PHILADELPHIA, PENNSYLVANIA, ASSIGNOR OF ONE-THIRD TO
IDA GOLDENBURG AND ONE-THIRD TO NATHAN GOLDENBURG, OF PHILADELPHIA,
PENNSYLVANIA.

GARMENT.

1,084,000.

Specification of Letters Patent.

Patented Jan. 13, 1914.

Application filed June 6, 1913. Serial No. 772,117.

To all whom it may concern:

Be it known that I, HENRY FOLKMAN, a citizen of the United States, residing at Philadelphia, in the county of Philadelphia and State of Pennsylvania, have invented 5 certain new and useful Improvements in Garments, of which the following is a specification.

My invention relates to improvements in 10 garments, and more particularly to an improved one piece dress designed primarily for use by school children, and formed with two overlapping front waist sections adapted to be arranged with either section on the 15 outside, and capable of reversing without opening the skirt of the dress.

A further object is to provide in a dress of the character stated, an improved construction and arrangement of parts at the 20 waist line which enables the front waist sections to be reversed and maintain a smooth and attractive waist line in either position.

A further object is to provide an improved 25 arrangement of ornamental collar with tabs thereon having snap button connection with the front waist sections, so that the appearance of the garment at the collar is precisely the same in either position of the garment.

With these and other objects in view, the invention consists in certain novel features of construction and combinations and arrangements of parts as will be more fully 35 hereinafter described and pointed out in the claims.

In the accompanying drawings: Figure 1 is a view in elevation illustrating my improved garment showing the free end of the 40 belt detached. Fig. 2 is a view in section on the line 2—2 of Fig. 1. Fig. 3 is a view in section on the line 3—3 of Fig. 1. Fig. 4 is a fragmentary view in section through the garment at the waist line showing the 45 belt in its normal position. Fig. 5 is a view similar to Fig. 1 showing the waist front sections reversed and with a portion of the front broken out to illustrate parts beneath. Fig. 6 is a view similar to Fig. 4 50 but showing the parts in their reversed position. Fig. 7 is a view in section on the line 7—7 of Fig. 5, and Fig. 8 is a view in section on the line 8—8 of Fig. 5.

My improved garment is of the single 55 piece type, but for clearness of description

I shall give the waist portion the reference numeral 1 and the skirt portion the reference numeral 2, but it is to be understood that these parts are secured together, and while the garment is primarily for use by 60 school children, I am of course not limited in this particular. At the juncture of the waist 1 and skirt 2, a belt 3 is attached by lines of stitching 4 which lines of stitching terminate short of one end of the belt which 65 leaves this belt end 5 free, and is secured in normal position by snap button members 6.

The waist 1 of the garment is made with two overlapping front sections 7 and 8, the former having its free edge 9 constituting 70 a continuation of the edge 10 of one side of the open skirt 2, said skirt being normally held together by suitable fastening devices. I have shown snap buttons 12 for the purpose. The front section 8 extends beyond 75 the edge 13 of the skirt, and the lower portion of this front section 8 is covered by the belt end 5 when said section 8 is on the outside. The waist section 8 and the belt 3 are secured to the skirt portion 2 by the lines of 80 stitching 4 hereinbefore referred to, and these lines of stitching terminate short of the edge 13 of the skirt, so that a projecting flap 14 is formed extending down the length of the skirt and forming an under-lying 85 portion for the reception of the snap button members and to insure a perfect closure of the skirt.

Waist 1 is provided around the neck opening with a collar 15, the ends 16 and 17 of 90 which being free from the garment, form tabs which are provided with snap button members 18 to engage snap button members 19 on sections 7 and 8 respectively to securely hold the sections in position. Other 95 snap buttons 20 are provided on the free ends of both sections 7 and 8 so that these free ends may be secured on the inside of the garment as well as on the outside thereof. Section 8 is preferably provided with a 100 series of pockets 21, so that various articles such as pencils, erasers, etc., may be carried, and as this garment is particularly adapted for use by school children, the pockets will be found a great convenience.

Along the edge 9 of section 7, snap button members 22 are provided and engage snap button members 23 on section 8, and as it is the intention to have this section 7 on the outside when the child is going to 110

and from school, it will be of course desirable to have this outer section more ornamental than the other section which is designed to be outermost when the child is in school, and which will necessarily become soiled.

Fig. 1 shows the dress with the sections 7 on the outside. To place this section 7 on the inside and position section 8 on the outside, the operation will be as follows: Snap buttons 18 are released and the ends 16 and 17 of the collar 15 thrown backward. Snap button 6 is released to free the end of the belt 4, snap buttons 22 are released to disengage the top of section 7 from the dress, and snap button 20 is then released to disengage the free end of section 8. Section 7 may be then placed on the inside and section 8 on the outside. The ends 16 and 17 are then folded down and snap buttons 18 engaged. The snap button 6 is then engaged to position the belt over the lower end of section 8, so that the dress will be held in this position when in school. As above stated, the section 8 terminates at its lower end under the belt end, so that the sections may be readily placed inside or outside as the case may be without affecting the skirt portion of the dress. A reversal of this operation will return the parts to former position, so that the child is ready for her journey home. It will therefore be noted that the sections 7 and 8 may be reversed without opening the garment below the waist, and that in either position, the belt end 5 will lie smooth at the waist, and the waist of the garment as well as the skirt will be smooth in either position of adjustment.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A one piece garment of the character described, consisting of a waist and skirt having a belt at the juncture of the waist and skirt, with one end of the belt free, said

waist having overlapping front sections, said front sections adapted to be reversed when the loose belt end is detached, said belt end when in normal position covering the lower portions of the waist front sections, a collar fixed to the waist extending part way around the waist at the neck and having a tab at its ends, and snap button members on said tabs and on said front sections locking the tabs to either of the front sections which is outermost, substantially as described. 55 60 65

2. A one piece garment of the character described, consisting of a waist and skirt having a belt at the juncture of the waist and skirt, with one end of the belt free, said waist having overlapping front sections, 70 said front sections adapted to be reversed when the loose belt end is detached, said belt end when in normal position covering the lower portions of the waist front sections, and one of said waist front sections extending beyond its point of attachment with the skirt at the waist, a collar fixed to the waist extending part way around the waist at the neck and having a tab at its ends, and snap button members on said tabs and on said front sections locking the tabs to either of the front sections which is outermost, substantially as described. 75 80

3. A one piece garment of the character described, comprising a waist and skirt open throughout their length, a belt around the waist of the garment with one end free, an extension on the skirt portion of the garment having snap button members thereon, other snap button members on the other edge 90 of the skirt adapted to engage said first-mentioned snap button members, said waist having two overlapping front sections, one front section extended beyond the said flap of the skirt section, securing devices adapted 95 to secure either of said front sections outermost, and said free end of the belt adapted to cover the lower end of the said extended front sections, substantially as described. 95

In testimony whereof I have signed my 100 name to this specification in the presence of two subscribing witnesses.

HENRY FOLKMAN.
